UNITED STATES PATENT OFFICE.

LEWIS T. CANFIELD, OF CHICAGO, ILLINOIS, ASSIGNOR TO UNION DRAFT GEAR CO., OF CHICAGO, ILLINOIS, A CORPORATION OF DELAWARE.

DRAFT GEAR.

Application filed April 28, 1926. Serial No. 105,140.

The invention relates to draft gears for railway cars, its objects being to secure high efficiency and simplicity of construction.

The invention consists in a structure such as is hereinafter described and as illustrated in the accompanying drawings, in which—

Fig. 1 is a detail plan view of the center frame members of a car, with the improved gear applied thereto, the gear being shown 10 in central plan section, in release position;

Figs. 2 and 3 are views in perspective of elements of the gear;

Fig. 4 is a central plan section of the gear under full compression;

Fig. 5 is a transverse section on the line 15 5—5 of Fig. 4; and

Fig. 6 is a central plan section of the gear, showing a modified form of construction.

The center or draft sills of a car are shown 20 at 10, a pair of draft lugs at 11—11, and a pair of buffing lugs at 12—12. There is used in connection with the gear a pair of plate followers 13, 14 which cooperate respectively with the draft and buffing lugs. The 25 butt of a drawbar is shown at 15 and the yoke or drawbar extension which encircles the gear is represented at 16. All of these parts are of any preferred construction.

The gear comprises a barrel 17 in the form 30 of a heavy helical spring formed of a coiled bar which is rectangular in cross-section, one of the faces of the bar forming the bore of the barrel. The ends of the barrel are seated against laterally extending flanges as 35 18, 19, of a pair of wedge blocks 20, 20, which flanges bear against the inner faces of the followers 13, 14.

Cooperating with the wedge blocks 20, 20 are a plurality of sector-shaped wedge shoes 40 21. As shown, the shoes of each set are three in number, each extending through approximately 120°, though a greater number may be employed if desired. The wedge faces of the blocks 20 correspond in number to 45 the shoes.

In the preferred form of construction each set of wedge shoes is enclosed within a longitudinally divided sectional shell 22, one element 23 of which is shown in perspective 50 in Fig. 2. While these shells are shown as comprising two elements each extending through 180°, it is obvious that they may be composed of a greater number of sections of correspondingly less circumferential extent. The shoes 21 are provided with longi-

tudinal extensions 24 projecting beyond the bases of the wedging portions and bearing against and conforming to the inner surfaces of the shells 22. Helical springs as 25 react between the head or wedge portions of the shoes 21 and end walls 26 of the shells 22. The inner ends or end walls 26 of the two shells 22 are always in contact and obviously corresponding elements of the two shells might be integrally united, the walls 26 forming a transverse web.

There is shown the usual axial assembling bolt 27 extending through the wedge blocks 20, the outer faces of which are recessed as shown to permit the use of a bolt of such length that it will not interfere with the full compression of the gear.

Normally the parts assume the positions as shown in Fig. 1. Upon the application of compressive forces either of draft or buff 75 one of the followers 13, 14 is advanced compressing the spring of which the barrel 17 is constituted and forcing the wedge shoes 21 radially outward against the walls of the shell elements, thus expanding the shells and 80 forcing them against the inner surface of the barrel. The shoes 21 are carried forward by the advancing follower against the resistance of the springs 25, the shoes at the opposite end of the gear being advanced against 85 the wedge block 20 with which they cooperate and expanding the shell by which they are enclosed. The shells are carried forward by the frictional engagement with them of the wedge shoes and against the frictional 90 resistance between them and the inner surface of the barrel.

The parts are so proportioned that when the gear is completely compressed they assume the relative positions as shown in Fig. 95 4, the spring constituting the barrel 17 being completely closed and the ends of the shells being in contact with the flanges as 17, 18 of the wedge blocks. Release is effected by the expansion of the spring forming 100 the barrel, and the springs 25 prevent a too violent action on release by holding the wedge faces of the shoes in contact with the wedge blocks.

In the construction illustrated in Fig. 6 105 the wedge blocks, wedge shoes and barrel may be as shown in the form already described. The shell, however, consists of a pair of longitudinally continuous sections 28, 29 cooperating with both sets of wedge 110

elements and not being provided with a transverse web. The central springs 30 react directly between the two sets of wedge shoes.

5 The action of the gear when made in this form will be the same as in the form of Fig. 1 except that upon release the shell is restored only by the frictional action and it may never return to the central position 10 shown in Fig. 6. The efficiency of the gear, however, will not be in any wise diminished because of the floating character of the shell.

15 While preferred forms of construction are shown various changes in detail may be made within the scope of the invention.

I claim as my invention:

1. In a draft gear, in combination, a barrel formed of a helical spring, a longitudinally divided shell inclosed within and frictionally engaging the barrel, a set of sector-shaped wedge shoes inclosed within each end of the shell, spring means resisting the relative approach of the two sets of shoes, wedge blocks cooperating with each set of shoes, and followers for advancing the blocks and longitudinally compressing the barrel.

2. In a draft gear, in combination, a barrel formed of a helical spring, a longitudinally divided shell inclosed within and frictionally engaging the barrel, a set of sector-shaped wedge shoes inclosed within each end of the shell, spring means resisting the relative approach of the two sets of shoes, wedge blocks cooperating with each set of 35 shoes and having laterally extending flanges

engaging the ends of the barrel, and followers for advancing the blocks and longitudinally compressing the barrel.

3. In a draft gear, in combination, a barrel formed of a helical spring, a longitudinally divided shell inclosed within and frictionally engaging the barrel and having a transverse wall midway of its ends, a set of sector-shaped wedge shoes inclosed within each end of the shell, springs reacting between the shell wall and the two sets of shoes, wedge blocks co-operating with each set of shoes and followers for advancing the blocks and longitudinally compressing the barrel.

4. In a draft gear, in combination, a barrel formed of a helical spring, friction elements engaging the inner surface of the barrel, wedge means for forcing the friction elements against the barrel, spring means resisting the advance of the wedge elements, and means for compressing the barrel longitudinally.

5. In a draft gear, in combination, a barrel consisting of a helical spring formed of a bar angular in cross-section, one face of the bar constituting the bore of the barrel, friction elements engaging the inner surface of the barrel, wedge means for forcing the friction elements against the barrel, spring means resisting the advance of the wedge elements, and means for compressing the barrel longitudinally.

In testimony whereof I affix my signature,

LEWIS T. CANFIELD.
